United States Patent Office.

ALFRED STEVENS, OF GEORGETOWN, ASSIGNOR TO JOSIAH STARLING,
OF MANHEIGAN, MAINE.

Letters Patent No. 97,325, dated November 30, 1869.

IMPROVEMENT IN MACHINE FOR PUTTING SEAMS OF VESSELS.

The Schedule referred to in these Letters Patent and making part of the same.

To all whom it may concern:

Be it known that I, ALFRED STEVENS, of Georgetown, in the county of Sagadahoc, and State of Maine, have invented a new and useful Improvement in Machines for Putting the Seams of Vessels; and I do hereby declare the following to be a full, clear, and exact description thereof, sufficient to enable those skilled in the art to which my invention appertains, to fully understand the same, reference being had to the accompanying drawing, forming part of this specification, and in which—

Figure 1 is a side view, in partial section,

Figure 2 is an inverted plan view, and

Figure 3, a transverse section of the improved seam-putting machine, the plane of section being indicated by the line $x x$ in fig. 1.

The subject of this invention is a machine or device, to be operated by hand, for filling the seams of vessels with putty.

The invention comprises several improvements on a seam-putting machine for which Letters Patent of the United States, bearing date August 3, 1869, and numbered 93,365, were granted to me as assignor to Josiah Starling. In the device referred to, the block or frame forming the body of the machine is made square at the ends, and so is the cavity in the block or frame. It has been found that this construction made the machine unnecessarily heavy, especially when the block is of cast-metal.

One of my present improvements consists in rounding the ends of the block, and also its inner end faces, so that the weight is considerably lessened, and, at the same time, the operation of the machine is rendered more effective.

Another feature of improvement, in the present case, consists in making the block, frame, or body of the machine in two parts, and connecting them together by means of pivoted links, whereas, in the former case, the block was made entire.

The advantage gained by this improvement is, the play allowed the scraper, whereby it may conform to all the irregularities of surface over which it may pass, a spring being provided, which presses on the part to which the scraper is attached.

In order that others may so understand my invention as to be able to make and use this device, I will now proceed to describe it in detail.

Referring to the drawing, in the several figures of which similar letters of reference indicate like parts—

A is the main portion of the machine, made of wood or metal, and having rounded ends, as clearly shown.

A cavity, the form of which is shown by dotted lines in fig. 1, is formed in the part A.

It will be seen that the dotted lines $a a$, representing the inner faces of the block, and the outer ends of the part A, are on the same curve.

In the bottom of part A is made a rectangular opening, in which are set two strips, B B, which are secured by screws $b b$, or in any other suitable manner.

c c are thin plates of metal, (tin, sheet-iron, or steel,) which I call "tires." These plates are fitted, as shown, over the strips B, and are secured thereto at $d d$, and bent down over the inside of the strips, so as to project below, thus leaving the tires free to play in the seam of the vessel.

In order to adjust the tires to seams of various widths, thumb-screws $b' b'$ are provided, which work through the strips B B, and the sides of the part A, and press against the tires, as shown in figs. 2 and 3.

C represents a gauge, of wood or metal, fixed in a groove in the bottom of part A, and projecting in front of the same. The office of this gauge is to clear out the seam, or press down the former filling, in advance of the tires, and to the same depth as they extend.

E E are followers, hinged together at f, the rod g, which connects the leaves of the hinge, being fitted in the sides of the box or part A, as shown in fig. 3.

These followers or blocks E are each provided with a lever, F.

The followers E, when pressed down, force the putty, with which the part or box A has been filled, out between the tires, and into the seam.

Springs h h are secured to the followers, to perfect their operation.

D is a presser or smoother, set in a groove in the bottom of part A, in line with the gauge C and tires. This device compresses and smooths the putty in the seam.

G represents a block, which is partially hollowed out, as shown in figs. 1 and 2.

This block is connected to the main part A by means of pivoted links i i.

H is a metallic scraper secured within the part G, and projecting below it. This scraper, coming after the presser or smoother D, removes all putty remaining outside on the edges of the seam.

I is a refuse-box, attached to the part G in such a position as to receive the scraps of putty detached by the scraper.

In a groove, j, in the under side of the part G, a smoother, represented in dotted lines, fig. 1, may be fitted. This smoother is in line with the presser D, the tires, and the gauge, attached to the main part A, and is used to make the putty smooth and even in the seam.

The object in attaching the part G to the main frame by means of pivoted connections is to give the scraper and finishing-smoother sufficient play to allow them to conform to the inequalities of surface over which it may pass.

In order to keep the part G, with its attached devices, down to its work, a spring, k, is employed, which

is attached to the lever F of the rear follower E, and presses on the top of the said block G, a space, l, being left in the rear end of the part A, to receive the spring k when the lever is fully depressed.

The operation is as follows:

The sides, ends, and bottom of the cavity in the part A are first well oiled, and the space is then filled with putty, the followers E being elevated, to give room for that purpose. The tires are now adjusted according to the size of the seam to be filled. The machine is then applied to the seam, the levers being held in the hands, the gauge, tires, and presser fitting in the seam. Now, move the machine steadily forward, at the same time pressing on the levers, and thereby forcing the putty down, through the opening between the tires, into the seam below, which has been prepared for its reception by the gauge. The tires, being flexible, will conform to all inequalities in the seam, and fill every part with putty, the first smoother will compress and harden the putty in the seam, the scraper removes all that remains outside on the edges, the detached scraps falling into the refuse-box, and the rear smoother will finish off the operation, leaving the putty smooth and even in the seam.

By means of this machine, the operation of putty-

ing seams will be greatly expedited, the labor lessened, and cost reduced, and, at the same time, the work will be properly performed.

Having thus described my invention,

What I claim as new, and desire to secure by Letters Patent, is—

1. The part G, which carries the scraper, finishing-smoother, and refuse-box, when connected to the main part A by means of pivoted links, substantially as herein described and shown, for the purpose specified.

2. In a seam-putting machine, the spring attached to the lever F, and pressing on the block G, substantially as described, for the purpose set forth.

3. The seam-putting machine herein described, composed of the part A, with rounded ends, and a receiving-cavity of the form described, the gauge, adjustable tires, followers E E, with levers F, and springs, the presser D, part G, with refuse-box, scraper, and finishing-smoother, and the pivoted links i, and spring k, all combined and arranged to operate substantially as herein shown and described.

ALFRED STEVENS.
